CLAIM

The ornamental design for a fire pit cover, as shown and described.

DESCRIPTION

FIG. 1 is a front perspective view of a fire pit cover, showing my design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged detail view of area 9 in FIG. 1; and,

FIG. 10 is an enlarged detail view of area 10 in FIG. 1.

(Continued)

The broken lines in the drawings depict portions of the fire pit cover that form no part of the claimed design.
